SAFETY REFLECTOR ASSEMBLY

Alan E. Brickman, Rostraver Township, Westmoreland County, Pa., and George A. Gleason, Worcester, Mass., assignors to The American Steel and Wire Company of New Jersey, a corporation of New Jersey

Application July 12, 1940, Serial No. 345,214

8 Claims. (Cl. 88—82)

This invention relates to highway safety reflectors, and particularly to an improved reflector assembly and method of mounting the same on highway guards.

This application is a continuation-in-part of applicants' application filed May 27, 1938, Serial No. 210,489.

Safety reflectors are now in common use for marking highways at various points, such as dangerous curves, the lateral limits of the highway, and the location of guard rails. Heretofore, such reflectors were mounted in the highway guard rails or posts, usually in the most simple and inexpensive manner possible. Consequently, they could be easily removed therefrom; and oftentimes were removed by vandals or small children. The removal of these safety reflectors not only defeated the purpose for which they were intended but worked a hardship on the highway departments and were expensive to replace. Various ways of mounting these reflectors to prevent the removal thereof have been suggested and used but none has been effective enough to prevent such vandalism. According to the present invention, there is provided a safety reflector assembly which can be conveniently mounted on a highway post or road guard, and any attempt to remove the reflector therefrom will result in the breaking of the reflector, thus making it useless as well as valueless and thereby discouraging such removal.

It is one of the objects of the present invention to provide an improved safety reflector assembly which is inexpensive and simple in its construction and, at the same time, very effective for the purpose intended.

It is another object of the invention to provide an improved safety reflector assembly consisting of a minimum number of parts and which, on assembly, will automatically seal the colored reflecting portion thereof from damage by the weather or other foreign elements.

It is a further object of the invention to provide an improved easy and inexpensive method of mounting a safety reflector assembly on the highway post or guard rail on which it is to be located, and at the same time making it difficult to remove.

It is still another object of this invention to provide an improved safety reflector assembly in which the reflector lens is held in position solely by frictional forces.

Various other objects and advantages of this invention will be more apparent in the course of

the following specification and will be particularly pointed out in the appended claims.

In the accompanying drawing, there is shown, for the purpose of illustration, an embodiment and a modification thereof which our invention may assume in practice.

In the drawing:

Figure 1 is a perspective of a type of highway guard rail post and bracket with which our improved safety reflector assembly may be incorporated;

Figure 2 is a side elevation of the parts of the improved reflector assembly showing them unassembled;

Figure 3 is a similar view, showing the method of assembling the same;

Figure 4 is an enlarged section of the bracket, showing the reflector assembly mounted therein;

Figure 5 is a rear view of the mounted reflector assembly; and

Figure 6 is an enlarged section similar to Figure 4, showing another manner in which the reflector lens can be assembled in the receptacle without the use of the rubber gasket.

The improved safety reflector assembly of our invention, as shown in the drawing, comprises a metallic cylindrical cup-like lens receptacle 2 having a flanged portion or lip 3 around the outer edge thereof and a cylindrical button-like reflector lens unit 4 preferably having a rearwardly tapered portion 5 which is adapted to fit into the receptacle 2 with preferably a pliable rubber gasket or washer 6 compressibly positioned therebetween. The button-like reflector glass lens is preferably of a one-piece construction, and has a circumferential or annular flange 9 arranged therearound intermediate the length thereof and a colored reflecting portion, preferably an aluminum spray fused on the extreme rear surface and rearwardly tapered portion thereof. It will be understood that any suitable type lens may be used with our invention but a colored glass lens as described above is preferably used as it makes a complete reflector button in itself and one that lends itself favorably to our invention.

The safety reflector button assembly of our invention is especially adaptable for use with resilient offset spring-type brackets, as shown at 7 in the drawing, which are attached to a number of suitable highway posts, as shown in Figure 1, which make up the guard rail, but may be adapted for use in any other desired manner.

To mount the button assembly in the resilient offset spring-type bracket, highway post, or

member with which it is to be used, the cup-like receptacle is first positioned in a suitable hole in the member 1 with the flange 3 flush against the outer surface thereof, as shown in Figure 3 of the drawing. The receptacle is then held therein and a plurality of projecting portions 8 struck up by means of a suitable tool from the material of the receptacle against the inner surface of the bracket 7, as clearly shown in Figures 3 and 5. This securely positions the cup-like receptacle 2 in the bracket.

The pliable rubber gasket or washer 6 is then positioned on the tapered portion 5 of the lens. This tapered portion, together with the rubber gasket 6 positioned thereon, is then placed in the receptacle, as shown in Figure 3, and forced therein so as to suitably press the rubber gasket between the tapered portion and the inner walls of the receptacle; that is, the tapered portion of the lens expands the gasket 6 and compresses it against the inner walls of the receptacle as the lens is forced therein. This results in frictionally holding the lens in position in the receptacle and completely seals the extreme rear colored portion of the lens from the weather and foreign elements. It is an advantage to have the rear portion of the lens sealed in such a manner, since, if it were open to the weather, it would tend to deteriorate the fused aluminum or colored reflecting portion, thereby diminishing its reflecting qualities.

It is preferable that the circumferential flange 9 have an outer diameter substantially equal to or slightly less than the inner diameter of the receptacle, as is clearly shown in Figures 4 and 6 of the drawing, so that a relatively tight or forced fit is assured between the flange and the inner periphery of the receptacle when the reflector button is forced therein so as to aid in securely holding the same in the receptacle solely by frictional forces. However, in certain instances, it may be desirable not to use the pliable rubber gasket 6 as shown in Figure 6 of the drawing, and in such case, the reflector button is forced into the receptacle and is held therein solely by the frictional forces exerted between the outer surface of the flange 9 of the reflector button and the inner periphery of the receptacle 2, due to the tight fit therebetween.

It will be seen that if it is desired to remove the reflector assembly from the bracket or mounting, should the lens in any way become damaged, a sleeve or other suitable tool may be positioned over and around the outside diameter of the cup-like receptacle and, when forced thereover, will inwardly compress the ears or projections 8, thereby allowing the complete assembly to be removed from the bracket or its mounting. It would be extremely difficult for anyone, especially children, to remove the lens from the receptacle in that they usually do not have suitable tools available for such use, and to attempt to remove the lens from the receptacle without breaking it would be futile.

While we have shown and described several embodiments of our invention, it will be understood that these embodiments are merely for the purpose of illustration and description, and that various other forms may be devised within the scope of our invention, as defined in the appended claims.

We claim:

1. The method of assembling a safety reflector on a metallic mounting member which comprises providing a lens receptacle having a flange

around the outer edge thereof, positioning said receptacle in a hole in said member so that the flange fits tightly against the outer surface of said member, striking up a plurality of projections from the material of the receptacle against the inside surface of said mounting member to securely hold the same therein, providing a button-like reflector lens having a rearwardly tapered portion, positioning a pliable sealing gasket on the tapered portion of said lens, and finally forcing said tapered portion together with said gasket into said receptacle where it is frictionally held solely by the action of said gasket between said lens and the inner wall of said receptacle.

2. A safety reflector assembly comprising a cylindrical lens receptacle, a cylindrical button-like reflector lens having a circumferential flange arranged therearound and a rearwardly tapered portion, and an annular pliable member, said lens being positioned in said receptacle with said pliable member positioned and compressed between said tapered portion and the inner walls of said receptacle at a spaced distance from said circumferential flange and with the circumferential flange therearound snugly fitting the inner periphery of said receptacle so that said lens will be held securely therein solely by frictional forces.

3. A safety reflector assembly comprising a cylindrical cup-like lens receptacle, a cylindrical reflector lens having a rearwardly tapered portion, and a relatively narrow annular resilient member, said lens being positioned in said receptacle with said resilient member positioned substantially centrally around the tapered portion of said lens and compressed between the same and the inner walls of said receptacle so that said lens is held securely therein by engagement of the annular member with the inner walls of said receptacle.

4. A safety reflector assembly comprising a cylindrical cup-like lens receptacle having one end thereof permanently closed, a cylindrical reflector lens having a rearwardly tapered reflector portion, and a relatively narrow annular rubber member, said lens being positioned in said receptacle with said annular member being positioned and compressed between the inner walls of said receptacle and the rearwardly tapered portion of the lens intermediate the ends of said tapered portion so as to securely hold the lens therein thereby completely sealing the most rearward portion of said lens against leakage so as to protect the same from the elements.

5. A safety reflector assembly comprising a cylindrical cup-like receptacle, and a cylindrical button-like reflector unit having an annular flange arranged therearound intermediate the length thereof with the flange having an outer diameter slightly less than the inner diameter of said receptacle, said unit being forced into position in said receptacle with the outer surface of the flange of said unit tightly fitting the inner periphery of said receptacle so that said unit is held securely therein by frictional forces exerted between said flange and said receptacle whereby the inner surface of said unit is sealed from the elements with the inner surfaces of said unit being spaced from the inner walls of said receptacle.

6. The method of assembling a safety reflector on a mounting member which comprises providing a cylindrical cup-like receptacle having a flange around the outer edge thereof, position-

ing said receptacle in a hole in the member in which the reflector is to be mounted so that the flange fits tightly against the outer surface of said mounting member, striking up a plurality of outwardly projecting portions from the body of said receptacle within said mounting member to hold the same therein, providing a cylindrical button-like reflector unit having an annular flange arranged therearound intermediate the length thereof, said flange having an outer diameter slightly less than the inner diameter of said receptacle, and finally positioning and forcing the unit into said receptacle so that the flange carried thereby tightly fits into said receptacle whereby the outer surface of the flange cooperates with the inner periphery of the receptacle and the unit is held therein solely by frictional forces.

7. A safety reflector assembly comprising a cylindrical-shaped receptacle having an open end and a closed end, and a cylindrical button-like reflector unit having an annular flange arranged therearound intermediate the length thereof, said unit being forced into position in said receptacle so that the flange carried by the unit is positioned at a point adjacent the open end of the receptacle with the outer surface of the flange tightly fitting the inner periphery of said receptacle so that said unit is held securely

therein by frictional forces exerted between said flange and said receptacle whereby the inner surface of said unit is sealed from the elements with the inner surfaces of said unit being spaced from the inner walls of said receptacle.

8. A safety reflector assembly comprising a cylindrical cup-like receptacle having an outwardly extending flange portion arranged around the periphery thereof at its open end, and a cylindrical button-like reflector unit having an annular flange arranged therearound intermediate the length thereof with the flange having an outer diameter slightly less than the inner diameter of said receptacle, said unit being forced into position in said receptacle so that the flange carried thereby is positioned at a point adjacent the open end of the receptacle immediately rearwardly of the flange portion carried thereby with the outer surface of the flange tightly fitting the inner periphery of said receptacle so that said unit is held securely therein by frictional forces exerted between said flange and said receptacle whereby the inner surface of said unit is sealed from the elements with the inner surfaces of said unit being spaced from the inner walls of said receptacle.
